(57) CLAIM

The ornamental design for a display screen with graphical user interface for online marketplace, as shown and described.

DESCRIPTION

The FIGURE is a front view of a display screen with graphical user interface for online marketplace.

The outermost broken-line perimeter illustrates a display screen and forms no part of the claimed design. The remaining broken lines illustrate portions of the graphical user interface and form no part of the claimed design.

1 Claim, 1 Drawing Sheet

The image shows a screenshot of a classifieds website. At the top, there is a decorative header featuring a cartoon character and the text "MISSOURI Classifieds". Below the header, the main navigation menu includes "Home", "Categories", and "Instructions". A search bar with the placeholder "What are you looking for?" is positioned next to the categories menu. To the right of the search bar is a "POST AN AD" button with a magnifying glass icon. The main content area is divided into several sections. On the left, a sidebar titled "Ad Categories" lists various categories with small icons: AUTOMOTIVE (car icon), BUSINESS (dollar sign icon), CLASSIFIED (key icon), COMMERCIAL (building icon), CONSTRUCTION (shovel icon), CRIMINAL (handcuffs icon), EDUCATION (book icon), FINANCIAL (dollar sign icon), FOOD (fork and knife icon), HEALTH (stethoscope icon), HOME & GARDEN (house icon), PET SERVICES (paw print icon), PERSONAL (person icon), REAL ESTATE (house icon), and VEHICLE (car icon). To the right of the sidebar, a large search bar is followed by a "All Categories" button and a magnifying glass icon. The main search results area is titled "ABOUT THIS SITE" and contains a brief description of the website's purpose: "This website is where Missouri residents and visitors can buy and sell items they no longer need. This website is where to buy and sell items you have in your home and items you no longer need." Below this, there are several "Recent Ads" listed, each with a thumbnail image, title, and a "View Ad" button. The ads include: "2006 Ford F150 XLT Super Cab", "2006 Ford F150 XLT Super Cab", "2006 Ford F150 XLT Super Cab", "2006 Ford F150 XLT Super Cab", "2006 Ford F150 XLT Super Cab", "2006 Ford F150 XLT Super Cab", "2006 Ford F150 XLT Super Cab", "2006 Ford F150 XLT Super Cab", "2006 Ford F150 XLT Super Cab", and "2006 Ford F150 XLT Super Cab". The bottom right corner of the page features a "Check here to add another ad." link and a "Privacy Policy" link.
